UNITED STATES PATENT OFFICE.

ISAAC C. LEVY, OF JACKSON, MICHIGAN.

TIE HANGER.

Application filed October 15, 1927. Serial No. 226,413.

The main object of this invention is to provide a tie hanger which is adapted to support a number of ties so that portions of each are visible and so that each tie hangs freely.

A further object is to provide a hanger having these advantages which may be collapsed without removing the ties, the ties being quite securely retained when in collapsed position for handling and storage as in a traveling bag or the like.

A still further object is to provide a hanger having these advantages which is compact, both when collapsed and also when erected.

Objects relating to details and economies of construction and operation of my invention will appear from the detailed description to follow.

The invention is defined and pointed out in the claims.

A structure which is a preferred embodiment of my invention is illustrated in the accompanying drawing, forming a part of this application, in which:

Fig. 1 is a front elevation of my improved hanger, a pair of ties being indicated by dotted lines.

Fig. 2 is a vertical section on a line corresponding to line 2—2 of Fig. 1, the hanger being shown as mounted on a wall or other support.

Fig. 3 is a view of the hanger collapsed, the supporting chain being partially broken away.

In the drawing similar reference characters refer to similar parts throughout the several views.

Referring to the drawing, my improved hanger comprises a base or cross piece 1 the ends of which are mounted by means of pivots 2, and a pair of side or hanger bars 3 having a pair of laterally projecting supporting arms 4 thereon.

These supporting arms are arranged in the plane of the side bars and have upturned outer ends 5 to retain the ties or the like indicated by the dotted lines 6.

The cross piece 1 is provided with a pair of inclined stops 7 at one side adapted to support the arms in an outwardly diverging relation, as shown in Fig. 1, when the hanger is supported by means of a chain or other suspending means 8. This chain 8 has a ring 9 at the center thereof adapted to receive a thumb tack 10 or the like.

One of the arms 3 is provided with an eye 11 to which the one end of the chain is secured, the chain, at its other end, having a hook 12 detachably engaging with the eye 11 of the other side bar.

The cross piece also has a pair of stops 13 projecting oppositely the stops 7, these stops 13 being adapted to support the bars 3 in an approximately parallel relation, as shown in Fig. 3, in which position the arms 4 project inwardly and the arms preferably being of such length that they abut when the structure is collapsed.

A strut 14 is provided for supporting the hanger in an inclined position, this strut having a cross piece 15 at its outer end and an offset 16 at its inner end, the offset being secured to the laterally projecting ear 17 on the cross piece by means of the pivot 18. Thus arranged, the offset provides a stop shoulder for supporting the structure in its erected position, as shown in Fig. 2, and permits the structure being folded over the cross piece to an approximately parallel relation and lying in the same direction as the side bars when they are collapsed, as shown in Fig. 3, thus providing compactness.

My improved hanger is very simple and economical in structure, is of considerable capacity and supports a plurality of ties so that portions of each are visible.

The structure may be collapsed without removing the ties from the supporting arms, it only being necessary to disengage the hook 12 and hold the hanger in an approximately horizontal position during the collapsing. The structure, however, should be first collapsed.

With the structure collapsed, as shown in Fig. 3, the ties are quite securely retained so that the hanger may be handled or thrown about considerably without disengaging the ties from their supporting arms, and the structure may be again erected with the ties in position.

Having thus described my invention, what I claim as new and desire to secure by Letters Patent, is:

1. A tie hanger comprising a cross piece, a pair of side bars pivotally mounted at the ends of said cross piece and each provided with a plurality of laterally projecting hanger arms disposed in the plane of said side bars, said cross piece having a pair of inclined stops at one side supporting said side bars in outwardly diverging relation

- with their arms projecting outwardly and a pair of stops on its other side supporting the said side bars in approximately parallel relation with their arms projecting inwardly, a flexible suspending means secured to the outer ends of said side bars and detachably connected to one of them, to the outer ends of said side bars and detachably connected to one of them, and a supporting strut pivotally mounted on said cross piece to be swung to erected position at an angle to the plane of said side bars or to a collapsed position in a plane approximately parallel to that of said side bars, said strut having an offset at its inner end, said cross piece having a laterally projecting ear to which said offset end is pivoted so that said strut may be swung over said cross piece when collapsed.
2. A tie hanger comprising a cross piece, a pair of side bars pivotally mounted at the ends of said cross piece and each provided with a plurality of laterally projecting hanger arms disposed in the plane of said side bars, said cross piece having a pair of inclined stops at one side supporting said side bars in outwardly diverging relation with their arms projecting outwardly and a pair of stops on its other side supporting the said side bars in approximately parallel relation with their arms projecting inwardly, a flexible suspending means secured to the outer ends of said side bars and detachably connected to one of them, and a supporting strut pivotally mounted on said cross piece to be swung to erected position at an angle to the plane of said side bars or to a collapsed position in a plane approximately parallel to that of said bars.
3. A tie hanger comprising a cross piece, a pair of side bars pivotally mounted at the ends of said cross piece and each provided with a plurality of laterally projecting hanger arms disposed in the plane of said side bars, said cross piece having a pair of inclined stops at one side supporting said side bars in outwardly diverging relation with their arms projecting outwardly and a pair of stops on its other side supporting the said side bars in approximately parallel relation with their arms projecting inwardly, and a flexible suspending means secured to the outer ends of said side bars and detachably connected to one of them, and a supporting strut pivotally mounted on said cross piece to be swung to erected position at an angle thereto, to a collapsed position in a plane approximately parallel to that of said side bars, said strut having an offset at its pivoted end so that it may be swung over said cross piece when collapsed.
4. A tie hanger comprising a cross piece, a pair of side bars pivotally mounted at the ends of said cross piece to be swung to either side thereof and each provided with a plurality of laterally projecting hanger arms, said cross piece having stops limiting the swing of said side bars, a suspending means at the outer ends of said side bars, and a supporting strut pivotally mounted on said cross piece to be swung to erected position at an angle thereto to a collapsed position in a plane approximately parallel to that of said side bars.
5. A tie hanger comprising a cross piece, a pair of side bars pivotally mounted at the ends of said cross piece to be swung to either side thereof and each provided with a plurality of laterally projecting hanger arms, said cross piece having stops limiting the swing of said side bars, a suspending means at the outer ends of said side bars, and a supporting strut pivotally mounted on said cross piece to be swung to erected position at an angle thereto to a collapsed position in a plane approximately parallel to that of said side bars.
6. A tie hanger comprising a cross piece, a pair of side bars pivotally mounted at the ends of said cross piece to be swung to either side thereof and each provided with a plurality of laterally projecting hanger arms, said cross piece having stops limiting the swing of said side bars, and a suspending means at the outer ends of said side bars, said arms being disposed substantially in the plane of said cross piece, the said stops being arranged to support said bars in outwardly diverging relation when they are swung to erected position and in approximately parallel relation with the arms end to end when swung to collapsed position.

In witness whereof I have hereunto set my hand.

ISAAC C. LEVY.
